UNITED STATES PATENT OFFICE.

CHARLEY VINCENT AND ALFRED FONTAINE, OF NEW HAVEN, CONNECTICUT.

WRENCH.

1,271,811.

Specification of Letters Patent.

Patented July 9, 1918.

Application filed August 15, 1917. Serial No. 186,427.

To all whom it may concern:

Be it known that we, CHARLEY VINCENT and ALFRED FONTAINE, citizens of the United States, residing at New Haven, in 5 the county of New Haven and State of Connecticut, have invented certain new and useful Improvements in Wrenches, of which the following is a specification, reference being had to the accompanying 10 drawings.

This invention comprehends certain new and useful improvements in wrenches, and relates particularly to wrenches of the quick adjustment type, the invention having for its primary object a practical, durable and efficient construction of device of 15 this character, the parts of which can be easily and cheaply manufactured and readily assembled and not liable to get out 20 of order.

A further object of the invention is an improved wrench comprising a rotatably mounted adjusting rod, engageable with a dog pivotally mounted in the relatively 25 movable jaw, and means for releasing the dog from the threads of the rod to secure the quick adjustment, the fine adjustment being secured by rotating the rod in the shank, and means being provided for conveniently locking the parts after the 30 desired adjustment has been effected.

And the invention also aims to generally improve devices of this class so as to render them more useful and commercially 35 desirable.

With these and other objects in view, as will more fully appear as the description proceeds, the invention consists in certain constructions, arrangements and combinations 40 of the different parts that we shall hereinafter more fully describe and claim.

For a full understanding of the invention reference is to be had to the following description and accompanying drawing, in 45 which—

Figure 1 is a side elevation of a wrench embodying the improvements of our invention,

Fig. 2 is a longitudinal sectional view 50 thereof with parts in side elevation,

Fig. 3 is a transverse sectional view on the line 3—3 of Fig. 2.

Fig. 4 is a similar view on the line 4—4 of Fig. 2.

55 Corresponding and like parts are referred to in the following description and accom-

panying drawing by like reference characters.

Referring to the drawing, the numeral 1 designates the relatively stationary jaw of 60 our improved wrench, and 2 designates the shank to which the jaw 1 is fixed and with which it is preferably integrally formed. Preferably the shank 2 is formed on one side face with linear graduations, as clearly 65 illustrated in the drawing.

The shank 2 is formed with a longitudinal bore or opening 3 terminating at one end in a socket 4 and communicating with a longitudinal recess or slot 5 formed on one 70 edge of the shank, as shown. A threaded rod 6 is rotatably mounted in the bore 3 of the shank 2 and provided at one end with a trunnion 7 which is mounted in the socket 4, said rod being secured to or formed 75 integrally with a handle 8 and provided, near said handle, with an annular groove 9.

A collar 10 is mounted upon one end of the shank 2 and is provided with an inwardly projecting tongue 11 fitting within 80 the slot 5 of the shank, said tongue having a transversely extending lug 12 formed thereon and fitting within the groove 9 of the threaded adjusting rod 6 whereby, after the collar is slipped upon the rod and upon 85 the shank and secured to the latter, the parts will be held in assembled relation and the rod mounted to rotate about its longitudinal axis.

13 designates the relatively movable jaw 90 of the wrench formed with a yoke 14 by which it is mounted to slide on the shank 2, and said jaw 13 has a dog 15 pivotally mounted therein, one end of the dog being threaded for engagement with the threads of 95 the rod 6, as indicated at 16. A spring-encircled rod 17 is carried by the jaw 13 and engages the relatively free end of the dog 15 whereby it is urged into engagement with the threads of the rod 6, and in order 100 to release the dog from the rod whereby a quick adjustment may be secured, we have provided pivotally mounted spring-pressed detent 18 which extends transversely through the jaw 13 to bear against the dog. An end 105 portion of the detent 18 extends exteriorly of the jaw 13 through a side thereof and is so arranged that by moving the detent 18 in one direction, the dog 15 may be swung out of engagement with the threaded rod 6. 110 Upon releasing the detent the springs 19 thereof will act as well as the spring-encir-

led rod 17, causing the dog to engage with the threads on the rod 6.

From the foregoing description in connection with the accompanying drawing, the operation of our improved quick adjustment wrench will be apparent. In the practical use of the device, by actuating the detent 18 the dog 15 may be released from the threaded rod 6 and the movable jaw 13 slid 10 toward or away from the stationary jaw 1 to effect a quick adjustment, and the finer adjustment may be obtained by turning the handle 8 to effect the rotation of the rod 6 in engagement with the dog 15.

15. Preferably the handle 8 is formed in one end with a circumferentially extending series of longitudinal notches or recesses 20, and the collar 10 carries a slide or catch 21 designed to engage in any of the recesses 20, 20 and thus lock the parts from movement.

While the accompanying drawing illustrates what we believe to be the preferred embodiment of our invention, it is to be understood that the invention is not limited 25 thereto, but that various changes may be made in the construction, arrangements and proportions of the parts without departing from the scope of the invention as claimed.

What is claimed, is:

30 1. A wrench of the character described, comprising a relatively fixed jaw, a shank connected thereto, said shank being formed with a longitudinal bore and in one edge with a longitudinal slot communicating 35 with the bore, a threaded rod rotatably mounted in said bore, a handle connected to one end of said rod, a collar fitting over one end of the shank and formed with an

inwardly projecting tongue engaging in said slot and formed with a lug, the rod 40 being formed with an annular groove in which said lug is engaged, a movable jaw slidably mounted on the shank and provided with a pivoted dog engageable with the threads of the rod, the handle being 45 formed in one end with a plurality of recesses, and a catch carried by the collar and engageable in any one of said recesses, for the purpose specified.

2. A wrench of the character described, 50 comprising a relatively fixed jaw, a shank connected thereto, said shank being formed with a longitudinal bore and in one edge with a longitudinal slot communicating with the bore, a threaded rod rotatably mounted in said bore, a handle connected to one end of said rod, a collar fitting over one end of the shank and formed with an inwardly projecting tongue engaging in said slot and formed with a lug, the rod being formed 55 with an annular groove in which said lug is engaged, a movable jaw slidably mounted on the shank and provided with a pivoted dog engageable with the threads of the rod, and coacting means carried by the collar and handle for holding the rod against 60 rotation.

In testimony whereof we hereunto affix our signatures in the presence of two witnesses.

CHARLEY VINCENT. [L.S.]
ALFRED FONTAINE. [L.S.]
